COUPLER

Edmund P. Kinne, Alliance, Ohio, assignor to
American Steel Foundries, Chicago, Ill., a cor-
poration of New Jersey

Application September 11, 1931, Serial No. 562,225

21 Claims. (Cl. 213—151)

The present invention relates to coupler de-
vices, and more particularly to the formation of
coupler contours pertaining to the A. R. A. stand-
ard No. 10 contour, and the like.

Among the objects of the present invention is
to provide a coupler contour adapted to effect
well defined results not obtainable with the exist-
ing coupler contours and heretofore unknown.
At the present time the existing contour lines are
10 determined preliminarily by standard require-
ments as to the desired horizontal and vertical
angling of the couplers. Under existing prac-
tice, however, it has been found that, although
the standard vertical angling between couplers is
15 substantially ideal for practical purposes, the
coupler contour provided for effecting such re-
sults leads to undesirable free slack between co-
operating couplers, which slack, in a train of
substantial length and comprising a large num-
20 ber of cars, is objectionable, undesirable, and
uncontrollable.

It is therefore an object of the present in-
vention to provide a novel means for decreasing
the amount of free slack, yet at the same time
25 maintaining the acceptable standard vertical
angling between couplers.

In an embodiment selected to illustrate the in-
vention, such results are effected by providing
30 curved tapered portions on the front face of the
knuckle, such tapered portions being adapted to
cooperate with the face of an adjacent coupler
head, constructed in accordance with the pres-
ent invention, for providing the desired vertical
35 angling.

The providing of curved tapered portions has
the further advantage of disposing curved round-
ed edges of the knuckle for contacting engage-
ment with the face of the opposing coupler head,
thereby preventing gouging and wear to said
40 face.

The invention further includes the idea of
providing a contour for a coupler face wherein
the cross-sectional area thereof varies increas-
45 ingly from the guard arm of the coupler head
to adjacent the ears thereof, thus distributing
additional metal at the most advantageous point
to prevent and eliminate breakage at this most
critical portion of the coupler head construction.

Another object within the purview of the in-
50 vention is to provide a knuckle having tapered
portions cooperating with the inclined or angu-
larly disposed face of an opposing coupler formed
as above indicated for decreasing slack, yet al-
lowing for the standard vertical angling there-
55 between, such tapered portions increasingly vary-

ing in depth or width in an opposite direction
to the direction of increase of the cross-sectional
area of the coupler face.

The invention still further contemplates the
idea of providing a coupler arrangement where-
in opposing couplers are provided with relatively
movable knuckles and have their contours so
formed that the pulling faces are in contacting
engagement when the couplers are in buff, where-
by the knuckles are not subjected to any tend-
ency to rotate inwardly of the head which other-
wise results in excessive wear and an accumula-
tion of free slack. The solid contacts between
the pulling faces of the knuckles while the cou-
plers are in buff further has the advantage of 10
distributing the buffing stresses over the entire
coupler faces, thereby lessening the breakages
through the coupler front faces.

It has also been found that under maximum
horizontal angling of couplers the now standard 20
requirement of approximately 15½ degrees is
excessive and that from 8 to 10 degrees is quite
sufficient.

The invention therefore has as an additional
feature the idea of forming the contour of the 25
heel of the knuckle, as likewise the ears of the
coupler head, so as to cut down the excessive hor-
izontal angling of opposing couplers and to fur-
ther effect an increase in the sectional area and
strength of the hub of the knuckle and coupler 30
ears.

With these and various other objects in view,
the invention may consist of certain novel fea-
tures of construction and operation, as will be
more fully described and particularly pointed
out in the specification, claims and drawings
appended hereto.

In the drawings, which illustrate an embodi-
ment of the device and wherein like reference
characters are used to designate like parts— 40

Figure 1 is a fragmentary top plan view of a
coupler construction embodying the invention,
the dotted lines indicating the corresponding
A. R. A. standard contour;

Figure 2 is a fragmentary top plan view dis-
closing two interengaging opposing couplers hav-
ing the contour disclosed in Figure 1 of the draw-
ings and showing the same in draft;

Figure 3 is a fragmentary horizontal cross-
sectional view of the couplers of Figure 2 and 50
showing the same in buff;

Figure 4 is a fragmentary top plan view of the
couplers of Figure 2 and disclosing the same in a
horizontally angled position;

Figure 5 is a fragmentary vertical cross-sec- 55

tional view through the opposing couplers of Figure 2 and disclosing the same in a vertically angled position;

Figure 6 is a fragmentary top plan view of a 5 coupler construction embodying a different coupler contour made in accordance with the present invention, the dotted lines indicating the corresponding A. R. A. contour;

Figure 7 is a top plan view of opposing couplers 10 incorporating the embodiment of the invention shown in Figure 6 of the drawings, and disclosing the same in draft;

Figure 8 is a fragmentary horizontal cross-sectional view of the opposing couplers shown 15 in Figure 7 of the drawings, and disclosing the same in buffing relation;

Figure 9 is a fragmentary top plan view of the opposing couplers disclosed in Figure 7 of the drawings, and showing the same in a horizontally angled position;

Figure 10 is a fragmentary vertical cross-sectional view through the opposing couplers shown in Figure 7 of the drawings, and disclosing the same in a vertically angled position; and

Figure 11 is a fragmentary view in cross-section of a car coupler made in accordance with the disclosure in Figures 6 to 10 inclusive of the drawings.

Referring now more in detail to the drawings, 30 and more in particular to Figures 1 to 5 inclusive, the present invention is shown in connection with a coupler construction having a contour substantially corresponding with the contour of a standard A. R. A. coupler, but varying therefrom for effecting new and different results, as will be more clearly brought out hereinafter. The A. R. A. coupler contour referred to in this specification and the claims is the No. 10 contour as shown in Figure 2528 on page 886 35 of the Car Builders Cyclopedia, 1931 edition. Referring to Figure 1, the standard A. R. A. coupler contour is shown in dotted lines as being formed in part by the coupler head 2 and in part by the knuckle 4. This contour is shown as originating in the end 6 of the guard arm 8 of the coupler head 2, and extending therefrom in a substantially straight line 10 to merge with a curved portion 12 of the front face 14 of the coupler head, the contour of the front face of the coupler being shown in this standard A. R. A. 40 contour in dotted lines merging into the coupler contour formed by the knuckle 4, as at 16. The contour of the standard A. R. A. knuckle is as shown in this figure, the contour forming the pulling face 18 of the knuckle nose, the face of the knuckle 20 and the heel or back of the knuckle 22.

As hereinbefore indicated, the present invention contemplates the idea of providing a contour which not only strengthens the front face of the coupler, but at the same time decreases the free slack between opposing couplers. Further, the invention includes the idea of decreasing the horizontal angling permitted between 45 opposing couplers, thereby making it possible to increase the strength of the knuckle and coupler head through the knuckle hub and ears thereof, respectively.

As shown in Figure 1, the proposed contour 50 for effecting these new and different results coincides with the contour of the standard A. R. A. coupler at the end of the guard arm, as likewise along the front face 10 of the guard arm. This new contour, however, departs from the old contour, as at 24, and extends, as shown in the

full line, substantially parallel to the front face 14, as at 26, and merges with the old contour adjacent the knuckle at 16. It will be seen that the new proposed contour adjacent the face of the coupler is disposed forwardly of the old contour, thereby effecting new results as will later be more fully explained.

The new contour for the knuckle 4 conforms with the standard A. R. A. knuckle contour from the point 16 around the nose and front face of the knuckle to a point 28 at the intersection of the surface of the face and heel or back of the knuckle. The new contour then flares outwardly in an increasing amount in a rearward direction, as at 30, to form the surface of the new 15 back of the knuckle or heel providing for the increased cross-sectional area between the points 32 and 16, or what is termed the hub of the knuckle, the ears (not disclosed) of the coupler head at this point being likewise flared to correspond substantially with the contour of the knuckle.

It will be seen from the above description, that the forward disposition of the new contour of the face of the coupler, as at 26, provides for 25 an increase of metal through this face, thereby tightening the contour between the coupler face and the nose of the knuckle 4. This provision, of course, decreases the amount of free slack 30 permitted between opposing couplers, and likewise would decrease the amount of vertical angling of these opposing couplers. In order to provide for the standard amount of vertical angling between opposing couplers, that has heretofore existed, the face 20 of the knuckle 4 is provided 35 with curved tapered portions 34 adjacent the upper and lower edges thereof, the tapering being substantially of the same magnitude as the increase of metal to the front face of the coupler. The invention comprehends the idea of providing these curved tapered portions, as shown in 40 Figure 5 of the drawings, so that the edges 36 of the knuckles are in spaced relation with the cooperating front face 26 of an opposing coupler to eliminate and prevent any possibility of gouging 45 of this face which would otherwise occur when the knuckles are in their maximum vertically angled position, as shown in this figure. When these knuckles are in their maximum vertically angled position as shown in Figure 5, the 50 opposite edges of the knuckles are in substantial contact, as at 40.

The outward disposition of the surface 30 of the back of the knuckle or heel relative to the surface 22 of the knuckle heel of a standard A. R. A. 55 contour decreases the amount of horizontal angling permitted between opposing couplers, as will be appreciated from the disclosure by reference to Figure 4 of the drawings. The outward disposition of the surface of the knuckle heel at 60 this point further increases the strength of the knuckle through the hub thereof, this portion of the knuckle being a critical or crucial point in the coupler construction.

In Figures 6 to 11 inclusive, is disclosed a modified form of the present invention varying from the present standard A. R. A. coupler as will be pointed out more fully hereinafter. As shown in Figures 6, 8 and 11, a coupler made in accordance with this modified form of the invention is shown superimposed upon the contour of a standard A. R. A. coupler shown in dotted lines and formed with the contour above described and shown in Figure 1 of the drawings, thereby more clearly depicting the variations between the new coupler 75

contour and the contour now existing in a standard A. R. A. coupler construction. The standard A. R. A. contour, as previously indicated, is shown as originating at the end of the guard arm 8 of a 5 coupler head 2, this contour extending along the face of the guard arm as at 10 which merges with the curved portion 12 of the face 14 of the coupler head 2, the contour of the face 14 extending around and merging at a point 16 with the contour formed by the knuckle 42. The contour of the knuckle 42 extends from the point 16 around the nose of the knuckle to form the pulling face 44 and the front face 46, the contour of the front face merging at 48 with the rearwardly extending 10 surface 50 of the back of the knuckle or heel.

The new proposed contour of the present embodiment coincides with the portions 6 and 10 of the standard A. R. A. contour for the guard arm to a point 52, the new contour diverging from the 20 old contour at this point and extending angularly relative to the front face 14 to form the front face 54 forwardly disposed relative to the face 14 and merging with the old contour again at the point 16. The contour of the knuckle 42 25 forms with the standard A. R. A. contour from the point 16 around the nose of the knuckle to the point 48, and then diverges or flares increasingly from this point relative to the surface 50 of the knuckle heel to form the back of the knuckle 30 or heel surface 56, this flaring being in a substantial nature the same as the flaring shown in Figure 1 of the drawings.

That part of the coupler contour of the present embodiment formed by the coupler head varies 35 from the corresponding contour shown in Figure 1 of the drawings, in that the front face 54 is formed so as to provide for additional material varying in width or thickness from the point 52 adjacent the guard arm to a point 58 adjacent 40 the knuckle 42 relative to the contour formed by the face 14 of the standard A. R. A. coupler face. This particular provision has the added advantage over the heretofore disclosed embodiment because of the fact that an increasing amount of 45 material is provided at the point 58, thereby effectively increasing the cross-sectional area through the front face of the coupler and decreasing breakage at this point which, experience 50 has taught, is a critical point in the construction of the coupler head.

As in the previous embodiment, the free slack between opposing couplers is decreased by this 55 additional material, and in order to provide for the standard amount of angling between these couplers, the knuckle 42 is beveled as at 60. Because of the fact that the front face 54 is angularly disposed, it is necessary to increasingly vary the depth or width of the tapered portion 61 from 60 a point 48 toward the guard arm 8.

In the present embodiment, as clearly shown 65 in Figure 11 of the drawings, the knuckle 42 is mounted in the coupler head 2 so as to have an amount of backlash "A" between a lock (not shown) engaging locking face 43 of the tail 45 and the wall 47 of the coupler head 2. Because 70 of this backlash which provides limited angular movement of the knuckle relative to the head, the knuckle in draft will assume the position shown in full lines in Figure 11 of the drawings, and when in cooperative buffering relation with a mating knuckle will angle in the coupler head to the position shown in dotted lines in Figure 11, thereby having substantially solid contact with the mating knuckle when in buffering relation there- 75 with and the front face of the opposing coupler.

As clearly shown in Figure 8 of the drawings, the movement permitted by the knuckles 42 in co-operation with the angular disposition of the coupler faces 54 effects contacting engagement or solid contacts between the pulling faces of the 5 opposing knuckles when these couplers are in buff. This solid contact between the noses of the knuckles and the buffering faces of the knuckles with the front face 54 of the coupler head effectively causes a more uniform and wider distribution of the buffering forces to the coupler constructions. The tendency, therefore, is to eliminate or practically do away with breakage 10 through the front faces of the coupler heads, thereby resulting in a substantial decrease in the 15 cost of operation, maintenance and replacement. As in the previously referred to embodiment, the addition of material to the back of the knuckle or heel, as at 56, causes a decrease in the permitted horizontal angling between opposing couplers, as likewise an increase in the strength of 20 the knuckle through the hub thereof and the increase in strength of the ears of the coupler head.

It is to be understood that I do not wish to be limited by the exact embodiment of the device 25 shown, which is merely by way of illustration and not limitation, as various and other forms of the device will of course be apparent to those skilled in the art without departing from the spirit of the invention or the scope of the claims. 30

I claim:

1. In a coupler arrangement, the combination of opposing couplers each having a coupler head and a knuckle adapted to be disposed in engaging relation, and means providing for engagement 35 between the pulling faces of said knuckles when each of said knuckles is in buffering engagement with the coupler head of an opposing coupler.

2. In a coupler arrangement, the combination of opposing couplers each having a coupler head 40 and a knuckle having limited angular movement therewith when in locked position, each of said couplers having the knuckle and head so formed and arranged as to effect movement of said knuckles to provide engagement between the pulling 45 faces of said knuckles when each of said knuckles is in buffering engagement with the coupler head of the opposing coupler.

3. In a coupler construction, the combination of a coupler head, a knuckle, and means for effecting engagement between the pulling face of said knuckle and the pulling face of a mating knuckle when said second-named knuckle is in buffering engagement with said coupler head. 50

4. In a coupler construction, the combination 55 of a coupler head, and a knuckle having limited angular movement therewith when in locked position, said knuckle and the front face of said coupler head being so constructed and arranged in spaced relation that the pulling face of a mating knuckle is adapted to have complete engagement with the pulling face of said first-mentioned knuckle when the mating knuckle is in complete buffering engagement with said front face. 60

5. In a coupler arrangement, the combination 65 of opposing couplers each having a coupler head and a knuckle adapted to be disposed in engaging relation, means providing for engagement between the pulling faces of said knuckles when each of said knuckles is in buffering relation with 70 the coupler head of the opposing coupler, each of said coupler heads having a front face normally spaced from the knuckle thereof to permit a limited amount of vertical angling between said opposing couplers, and means providing for an 75

increased amount of vertical angling between said couplers.

6. In a coupler arrangement, the combination of opposing couplers each having a coupler head and a knuckle adapted to be disposed in engaging relation, means providing for engagement between the pulling faces of said knuckles when each of said knuckles is in buffing relation with the coupler head of the opposing coupler, each of said coupler heads having a front face normally spaced from the knuckle thereof to permit a limited amount of vertical angling between said opposing couplers, and means on the face engaging portion of the knuckles to permit an increased amount of vertical angling between said couplers.

7. In a coupler arrangement, the combination of opposing couplers each having a coupler head and a knuckle adapted to be disposed in engaging relation, means providing for engagement between the pulling faces of said knuckles when each of said knuckles is in buffing relation with the coupler head of an opposing coupler, each of said coupler heads having a front face normally spaced from the knuckle thereof to permit a limited amount of relative longitudinal translatory movement and vertical angling between said opposing couplers, said knuckles having portions of the face engaging portion thereof so disposed as to permit an increased amount of vertical angling.

8. In a coupler arrangement, the combination of opposing couplers each having a coupler head and a knuckle having limited angular movement therewith when in locked position, each of said coupler heads having a front face normally spaced from the knuckle thereof to permit a limited amount of relative longitudinal translatory movement and vertical angling between said opposing couplers, each of said couplers having the knuckle and head so formed and arranged as to effect movement of said knuckles to provide engagement between the pulling faces of said knuckles when the same are in buffing relation with the front face of the opposing coupler, and means providing for an increased amount of vertical angling between said couplers.

9. In a coupler arrangement, the combination of opposing couplers each having a coupler head and a knuckle having limited angular movement therewith when in locked position, each of said coupler heads having a front face normally spaced from the knuckle thereof to permit a limited amount of relative longitudinal translatory movement and vertical angling between said opposing couplers, each of said couplers having the knuckle and head so formed and arranged as to effect movement of said knuckles to provide engagement between the pulling faces of said knuckles when the same are in buffing relation with the front face of the opposing coupler, and means on the face engaging portion of the knuckles to permit an increased amount of vertical angling between said couplers.

10. In a coupler arrangement, the combination of opposing couplers each having a coupler head and a knuckle having limited angular movement therewith when in locked position, each of said coupler heads having a front face normally spaced from the knuckle thereof to permit a limited amount of relative longitudinal translatory movement and vertical angling between said opposing couplers, each of said couplers having the knuckle and head so formed and arranged as to effect movement of said knuckles to provide engagement between the pulling faces of

said knuckles when the same are in buffing relation with the front face of the opposing coupler, said knuckles having portions of the face engaging portion thereof so disposed as to permit an increased amount of vertical angling.

11. In a coupler construction, the combination of a coupler head, a knuckle, means providing for engagement between the pulling faces of said knuckle and a mating knuckle when in buffing relation, said coupler head having a front face normally spaced from said first-named knuckle to permit a limited amount of relative longitudinal translatory movement and vertical angling of said mating knuckle between said face and said knuckle, and means providing for an increased amount of vertical angling.

12. In a coupler construction, the combination of a coupler head, a knuckle, means providing for engagement between the pulling faces of said knuckle and a mating knuckle when in buffing relation, said coupler head having a front face normally spaced from said first-named knuckle to permit a limited amount of relative longitudinal translatory movement and vertical angling of said mating knuckle between said face and said knuckle, and means on the face engaging portion of the knuckle to permit an increased amount of angling.

13. In a coupler construction, the combination of a coupler head, a knuckle having limited angular movement therewith when in a locked position, said coupler head having a front face normally spaced from said knuckle to permit a limited amount of relative longitudinal translatory movement and vertical angling of a mating knuckle between said face and said first-mentioned knuckle, said coupler having a knuckle and a front face so disposed and arranged in spaced relation that the pulling face of a mating knuckle is adapted to have complete engagement with the pulling face of said first-named knuckle when the mating knuckle is in complete buffing engagement with said front face, and means providing for an increased amount of vertical angling.

14. In a coupler construction, the combination of a coupler head, a knuckle having limited angular movement therewith when in a locked position, said coupler head having a front face normally spaced from said knuckle to permit a limited amount of relative longitudinal translatory movement and vertical angling of a mating knuckle between said face and said first-mentioned knuckle, said coupler having a knuckle and a front face so disposed and arranged in spaced relation that the pulling face of a mating knuckle is adapted to have complete engagement with the pulling face of said first-named knuckle when the mating knuckle is in complete buffing engagement with said front face, and means on the face engaging portion of the knuckle to permit an increased amount of angling.

15. In a coupler construction, the combination of a coupler head, a knuckle having limited angular movement therewith when in a locked position, said coupler head having a front face normally spaced from said knuckle to permit a limited amount of relative longitudinal translatory movement and vertical angling of a mating knuckle between said face and said first-mentioned knuckle, said coupler having a knuckle and a front face so disposed and arranged in spaced relation that the pulling face of a mating knuckle is adapted to have complete engagement with the pulling face of said first-named knuckle.

when the mating knuckle is in complete buffing engagement with said front face, said knuckle having portions of the face engaging portion thereof so disposed as to permit an increased 5 amount of vertical angling.

16. In a coupler construction, the combination of a coupler head, and a knuckle mounted in said coupler head, said knuckle and coupler head being so constructed and arranged that the pulling 10 face of a mating knuckle is adapted to have complete engagement with the pulling face of said first-named knuckle when the mating knuckle is in complete buffing engagement with said coupler head.

15 17. In a coupler construction, the combination of a coupler head, and a knuckle, said knuckle being of such a construction and so mounted in said coupler head that the pulling face of a mating knuckle is adapted to have complete 20 engagement with the pulling face of said first-named knuckle when the mating knuckle is in complete buffing engagement with said coupler head.

18. In a coupler construction, the combination 25 of a coupler head, and a knuckle mounted in said coupler head, said knuckle and coupler head being so constructed and arranged and said knuckle being so mounted in said head that the pulling face of a mating knuckle is adapted to have complete 30 engagement with the pulling face of said first-named knuckle when the mating knuckle is in complete buffing engagement with said coupler head.

35 19. In a coupler construction, the combination of a coupler head, and a knuckle mounted in said coupler head, said knuckle and coupler head being so constructed and arranged that the pulling face of a mating knuckle is adapted to have complete engagement with the pulling face of said first-

named knuckle when the mating knuckle is in complete buffing engagement with said coupler head, said coupler head having a front face normally spaced from said first-named knuckle to permit a limited amount of relative vertical 5 angling of said mating knuckle between said face and said knuckle, and means providing for an increased amount of vertical angling.

20. In a coupler construction, the combination of a coupler head, and a knuckle, said knuckle 10 being of such a construction and so mounted in said coupler head that the pulling face of a mating knuckle is adapted to have complete engagement with the pulling face of said first-named knuckle when the mating knuckle is in 15 complete buffing engagement with said coupler head, said coupler head having a front face normally spaced from said first-named knuckle to permit a limited amount of relative vertical 20 angling of said mating knuckle between said face and said knuckle, and means providing for an increased amount of vertical angling.

21. In a coupler construction, the combination of a coupler head, and a knuckle mounted in said coupler head, said knuckle and coupler head being 25 so constructed and arranged and said knuckle being so mounted in said head that the pulling face of a mating knuckle is adapted to have complete engagement with the pulling face of said first-named knuckle when the mating knuckle is 30 in complete buffing engagement with said coupler head, said coupler head having a front face normally spaced from said first-named knuckle to permit a limited amount of relative vertical 35 angling of said mating knuckle between said face and said knuckle, and means providing for an increased amount of vertical angling.

EDMUND P. KINNE.
